UNITED STATES PATENT OFFICE.

WILLIAM F. CLARK, OF SAN FRANCISCO, CALIFORNIA.

DESIGN FOR A LABEL.

SPECIFICATION forming part of Design No. 33,712, dated December 11, 1900.

Application filed November 1, 1900. Serial No. 35,184. Term of patent 14 years.

To all whom it may concern:

Be it known that I, WILLIAM F. CLARK, a citizen of the United States of America, residing in the city and county of San Francisco, in the State of California, have invented and produced a new and original Design for a Label, of which the following is a full, clear, and exact description, reference being had to the accompanying drawing, forming part thereof.

This design is intended for a label.

As shown in the drawing, the leading or material features of my design consist of a shield-shaped figure with an ornamental border of scrollwork arranged on one side of the center and the pictorial representation of the globe on the opposite side of the center of a label of rectangular outline.

The ground of the label outside the scroll-shaped shield or figure and surrounding the globe is filled with or occupied by the flags of various nations, in close order or arrange-

ment, flowing free with the wind and covering to a great extent the background.

The flags represented are those of the leading nations of the world, and the background not covered by them is given a contrasting color.

On the surface of the globe are represented the divisions of land and water of the Eastern and Western Hemispheres in appropriate tints or colors.

Having thus described my invention, what I claim as new, and desire to secure by Letters Patent, is—

The design for a label as herein described and shown.

In testimony that I claim the foregoing I have hereunto set my hand and seal.

WILLIAM F. CLARK. [L. S.]
